UNITED STATES PATENT OFFICE

118,065

DESIGN FOR A TOASTER OR THE LIKE

Oscar M. Anderson and Nils T. Almquist, New Britain, Conn. assignors to Landers, Frary & Clark, New Britain, Conn., a corporation of Connecticut

Application December 1, 1938, Serial No. 81,495

Term of patent 7 years

To all whom it may concern:

Be it known that we, Oscar M. Anderson, a subject of the King of Sweden, and Nils T. Almquist, a citizen of the United States, both residents of New Britain, in the county of Hartford, State of Connecticut, have invented a new, original, and ornamental Design for a Toaster or the like, of which the following is a specification, reference being had to the accompanying drawing, forming a part thereof.

In the drawing, the figure is a perspective view of a toaster or the like, showing our new design.

The dominant feature of the design resides in the base portion of the toaster or the like shown in full lines.

We claim:

The ornamental design for a toaster or the like, substantially as shown and described.

OSCAR M. ANDERSON.
NILS T. ALMQUIST.
